UNITED STATES PATENT OFFICE.

EDWARD J. FESER AND MICHEAL L. PEOPLES, OF PHILADELPHIA, PENNSYLVANIA.

TOY GUN.

1,266,243.

Specification of Letters Patent.

Patented May 14, 1918.

Application filed October 23, 1917. Serial No. 198,009.

To all whom it may concern:

Be it known that we, EDWARD J. FESER and MICHEAL L. PEOPLES, citizens of the United States, residing at Philadelphia, in the county of Philadelphia and State of Pennsylvania, have invented certain new and useful Improvements in Toy Guns, of which the following is a specification.

One object of our invention is to provide a toy gun which is well adapted to shoot flies or other insects.

Another object is to so construct our invention that it can be quickly and cheaply manufactured.

15 A further object is to so construct our improved gun that it will be durable and so that the several parts can be readily assembled or detached.

20 A still further object is to so design our improved gun that it will be neat in outward appearance and will be free of objectionable projections.

These objects, and other advantageous ends which will be described hereinafter, we 25 attain in the following manner, reference being had to the accompanying drawings in which—

Figure 1 is a longitudinal sectional elevation of our improved gun,

30 Fig. 2 is a transverse section on the line 2—2 of Fig. 1, drawn on an enlarged scale.

Fig. 3 is a transverse section taken on the line 3—3 of Fig. 1, drawn on an enlarged scale,

35 Fig. 4 is a section taken on the line 4—4 of Fig. 1, drawn on an enlarged scale,

Fig. 5 is a section taken on the line 5—5 of Fig. 1, drawn on an enlarged scale,

40 Fig. 6 is a side view of a wire trigger which forms a part of our invention.

Fig. 7 is an end elevation of Fig. 6.

Fig. 8 is a top plan view of Fig. 6.

45 Fig. 9 is a top plan view of the casing of our improved gun as it appears when cut from a sheet of metal and before it is bent into the shape illustrated in Figs. 1 to 5, inclusive,

50 Fig. 10 is a top plan view of an auxiliary housing showing the same as it appears when cut from a sheet of metal and before it is bent,

Fig. 11 is a rear end elevation of the housing shown in Fig. 10 after the same is bent,

Fig. 12 is a side elevation of Fig. 11.

55 Fig. 13 is a top plan view of Fig. 12,

Fig. 14 is a fragmentary section of one end of a tubular plunger which forms a part of our invention,

Fig. 15 is a top plan view of a securing member for said tubular plunger, illustrated 60 as it appears when cut from a sheet of metal and prior to being bent,

Fig. 16 shows in section the securing member of Fig. 15 after the latter has been bent and also shows a fragmentary section of an 65 actuating spring and the manner in which the actuating spring is fixed to the securing member,

Fig. 17 is a transverse section taken on the line 17—17 of Fig. 16,

70 Fig. 18 is an enlarged fragmentary view of the end of the barrel portion of the casing when bent into its proper shape and including off-set or bayonet slots,

Fig. 19 is a view of a flanged bushing or 75 sleeve for retaining the opposite end of the spring shown in Fig. 16 and adapted to be secured to the end of the barrel shown in Fig. 18.

Fig. 20 shows an enlarged end view of a 80 projectile which is especially adapted for killing flies or insects, and

Fig. 21 is a section taken on the line 21—21 of Fig. 20.

Referring to the drawings, 1 represents a 85 casing which is preferably made by stamping the same out of a flat sheet of metal. This casing includes an integral barrel 2 and a stock section 3, the latter being bifurcated at its rear end to produce two side wings 4 90 and 5 to which the butt 6 of the gun is inserted when the casing is bent in the positions clearly illustrated in Figs. 1 to 5 inclusive. The casing 1 when bent has its edges 7 and 8 positioned at the bottom to 95 form a seam 9 and this seam is preferably soldered so as to make the entire casing practically integral at the bottom.

The barrel 2 at its free end has bayonet or off-set slots 10. A sleeve or bushing 11 100 having a flange 12 is adapted to snugly fit within said end of the barrel 2 so that the flange 12 abuts the extreme outer edge 13 of the barrel. Pins 14 are secured to the sleeve 11 and after the latter has been 105 pushed within the barrel 2 it is turned to move pins 14 into the off-set portion of the slots 10 and can be permanently secured, by a few drops of solder, to the barrel 2.

One end of a long coiled spring 15 is se- 110

cured in the present instance by solder 16 within the sleeve 11 prior to the insertion of the sleeve within the barrel 2.

A securing member 17 is preferably stamped out of a flat piece of sheet metal as shown in Fig. 15. This securing member includes an elongated plate 18 and lateral extensions 19 and 20. These extensions 19 and 20 are bent in opposite directions substantially in the arc of a circle, such for example as shown in Fig. 17, the portion 21 of the elongated plate 18 acting as a partition extending between the curved portions 19 and 20. This partition 21 is adapted to be pushed within diametrically opposite slots 22 in the contracted end 23 of a tubular plunger 24, as clearly shown in Figs. 1, 2, and 14. When in this position the opposite end of the coiled spring 15 is secured preferably by solder 25 to the outer surfaces of the curved lateral extensions 19 and 20. The elongated plate 18 is bent at an incline as shown at 26 and is provided with a hook 27 at its outer end.

An auxiliary housing 28 is preferably cut from a sheet of flat metal as shown in Fig. 10 and afterward bent in the positions shown in Figs. 1, 3, 11, 12, and 13. When bent, this housing includes two substantially parallel sides 29 and 30 which are spaced apart, as clearly shown in Figs. 3 and 11, and have upturned lower edges 31 and 32 respectively which embrace and are preferably secured by solder to opposite sides 33 and 34 at the bottom of the casing 1, as clearly shown in Figs. 1 and 3. The housing 28 includes a tongue 35 which projects forwardly of the sides 29 and 30 and has its end 36 turned under to form a receptacle for the front end 37 of a flat spring 38. The spring 38 passes rearwardly under the tongue 35 and we preferably provide a band 39 which passes under the spring 38 and through notches 40 in the tongue 35. The spring 38 has a bowed portion 41 which is positioned between the sides 29 and 30 of the housing 28.

A trigger 42 is, as illustrated, made of a single piece of wire which includes a double eyelet 43 and a doubled finger-engaging portion 44, an extension 45 springing from between the eyelets 43. The extension 45 includes a shoulder 46 which is adapted to pass upwardly through a hole 47 in the top of the housing 28.

A pivot pin 48 extends through the casing 1 and through holes 49 in the oppositely disposed sides 29 and 30 of the housing 28. This pivot pin 48 forms the pivotal support for the trigger 42 and passes through the eyelets 43. The hook 27 on the securing member 17 is adapted to engage to the rear of the shoulder 46 when the tubular plunger 24 has been pushed within the barrel 2 against the action of the coiled spring 15;

thus holding the plunger within the barrel of the gun under the tension of the attenuating spring 15. The bowed portion 41 of the spring 38 engages under the extension 45 of the trigger 42 and holds the shoulder 46 in an upward position to prevent accidental downward movement of the latter.

The outer end of the tubular plunger 24 slidably passes through the outer end of the coiled spring 15 which is secured within the sleeve 11. This outer end of the tubular plunger 24 has fingers 50 which engage the flange 12 of the sleeve 11 and thereby limit the inward movement of the tubular plunger 24.

A projectile 51 includes a wire stem 52 which has a forked end 53. A ring 54 has a flanged portion 55 which embraces the outer edge portion of a wire screen 56. The forked end 53 has portions 57 and 58 which are bound between the flanged portion 55 of the ring 54 and the screen 56, as clearly shown in Figs. 21 and 22. The stem 52 is adapted to be inserted within the outer end of the tubular plunger 24 after the latter has been pushed within the barrel 2 against the tension spring 15. Upon the movement of the trigger the shoulder 46 will be moved downwardly through the hole 47 out of engagement with the hook 27, thereby freeing the latter. The spring 15 will then contract and move the tubular plunger 24 outwardly and with it the projectile 51. The projectile being free will be ejected from the tubular plunger 24 after the latter has come to a sudden stop.

By including the wire screen 56 on the projectile, it is possible to shoot the projectile to kill flies or other insects lodging on the wall or ceiling. We preferably provide a trigger guard 59 which can be made of flat strip metal including at one end a hook 60 which extends through an opening 61 in the bottom of the casing and embraces the edge portion 62. The opposite end 63 of the guard is preferably soldered to the under portion of the casing, as clearly shown in Fig. 1. Also the trigger extension 45 at the opposite side of the shoulder 46 has an inclined portion 46* to permit the hook 27 to freely ride thereover when the tubular plunger 24 is pushed within the barrel 2.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:

1. A gun including a casing; a plunger;

- means for automatically moving the plunger; an auxiliary housing within the casing and having a hole therein; a securing member connected to the plunger and located 5 outside of said housing; a trigger mounted within said housing and having an extension provided with a shoulder adapted to be projected through the hole in the auxiliary housing; and a spring having a portion 10 within said housing for moving said shoulder into holding engagement with said securing member, substantially as described.
2. A gun including a casing having an opening in its bottom; a plunger; means for 15 automatically moving the plunger; an independent auxiliary housing within the casing and having portions extending through said opening and attached to the casing; a securing member connected to the plunger; a trigger mounted within said housing and having an extension provided with a shoulder adapted to be projected through the hole in the auxiliary housing; and a spring having a portion 20 within said housing for moving said shoulder into holding engagement with said securing member, substantially as described.
- 25 3. A gun including a casing having an opening; an auxiliary housing within said casing and having sides extending out of said opening with upturned edges embracing the outer sides of the casing adjacent said opening; and a trigger operatively mounted between the sides of said housing, substantially as described.
- 30 4. A gun including a casing having an opening; a removable independent auxiliary housing within said casing and having sides with upturned edges embracing the outer sides of the casing adjacent said opening; a trigger operatively mounted between the 35 sides of said housing; an automatically operative member within said casing and outside of said housing, said housing having an opening through which a portion of said trigger moves and is guided to retain said member; and a spring having an operative portion located between the sides of said housing and for holding said portion of the trigger in a position to secure said member, substantially as described.
- 40 5. A gun including a casing; an independent auxiliary housing mounted within the casing and having sides spaced apart and secured to the casing; a trigger operatively mounted between the sides of said housing; an automatically operative member within said casing, a portion of said trigger being movable into a position to hold said member, said housing having a tongue projecting therefrom; and a spring secured to said tongue at a position outside of said housing
- and having an operative portion located between the sides of said housing and adapted to move and hold said portion of the trigger into a retaining position to hold said member, substantially as described. 70
6. A gun including a casing; an auxiliary housing mounted within the casing and having sides spaced apart and secured to the casing; a trigger operatively mounted between the sides of said housing; an automatically operative member within said casing, a portion of said trigger being movable into a position to hold said member, said housing having a tongue projecting therefrom and including a turned portion located outside of said housing; a spring having a portion extending within said turned portion of the tongue; and a band surrounding said tongue and spring and positioned outside of said housing for preventing lateral movement of the latter with respect to the tongue, said spring having an operative portion positioned between the sides of the housing and adapted to move and hold said portion of the trigger into a retaining position to 80 hold said member, substantially as described.
7. A gun including a casing; an auxiliary housing mounted within the casing and having sides spaced apart and secured to the casing; a trigger operatively mounted between the sides of said housing; an automatically operative member within said casing, a portion of said trigger being movable into a position to hold said member, said housing having a tongue projecting therefrom and including a turned portion located outside of said housing; a spring having a portion extending within said turned portion of the tongue; and a band surrounding said tongue and spring and positioned outside of said housing for preventing lateral movement of the latter with respect to the tongue, said spring having an operative portion positioned between the sides of the housing and adapted to move and hold said portion of the trigger into a retaining position to 90 hold said member, substantially as described.
8. A gun including a casing; an auxiliary housing mounted within the casing and having sides spaced apart and secured to the casing; a trigger operatively mounted between the sides of said housing; an automatically operative member within said casing, a portion of said trigger being movable into a position to hold said member, said housing having a tongue projecting therefrom and including a turned portion located outside of said housing; a spring having a portion extending within said turned portion of the tongue; and a band surrounding said tongue and spring and positioned outside of said housing for preventing lateral movement of the latter with respect to the tongue, said spring having an operative portion positioned between the sides of the housing and adapted to move and hold said portion of the trigger into a retaining position to 100 hold said member, substantially as described.
9. A gun including a casing; an automatically movable member mounted within said casing; a trigger mounted within said casing and consisting of a single piece of wire having a doubled portion to form a finger hold, each strand of the folded portion having an eyelet bent therein, said eyelets being arranged side by side, and an extension located in a plane passing between said eyelets and having a shoulder bent therein; and a pivot member within said casing and passing through said eyelets, substantially as described. 115
10. A gun including a casing; a tubular plunger within the casing and having a slot formed in one end; means for automatically 120
11. A gun including a casing; a tubular plunger within the casing and having a slot formed in one end; means for automatically 125
12. A gun including a casing; a tubular plunger within the casing and having a slot formed in one end; means for automatically 130

- moving the plunger; a securing member having lateral extensions bent in curved formation and including a central partition, said central partition adapted to be projected within the slot in said plunger, said curved extensions being adapted to surround the slotted end of said plunger; and holding means adapted to be moved into securing engagement with said securing member, substantially as described.
10. A gun including a casing; an automatically movable member within the casing; and a projectile having a stem adapted to be inserted within said casing to be ejected from the casing by the automatically movable member, said projectile including a screen, substantially as described.
11. A gun including a casing; an automatically movable hollow member within the casing; and a projectile having an elongated
- stem adapted to be freely inserted within and entirely removed from said member, said projectile including a wire screen, substantially as described.
12. A gun including a casing; an automatically movable member within the casing; and a projectile having a stem adapted to be freely inserted within said member and including a screen and a ring binding said screen and a portion of said stem together, substantially as described. 25
- In testimony whereof we have signed our names to this specification in the presence of two subscribing witnesses.
